(57) **CLAIM**

The ornamental design for a integrated drip edge, as shown and described.

DESCRIPTION

FIG. 1 is a top perspective view of our integrated drip edge; FIG. 2 is a right side view thereof, the left side view being a mirror image thereof; FIG. 3 is a front view thereof; FIG. 4 is a rear view thereof; FIG. 5 is a top view thereof; and, FIG. 6 is a bottom view thereof.

In FIGS. 1 and 3 through 6 the integrated drip edge is cut to indicate indeterminate length.

A pair of optional hinges are shown in broken line in FIGS. 1 and 2 and form no part of the claimed design.

A portion of a board to which the integrated drip edge is attached is shown in broken line in FIG. 2 and forms no part of the claimed design.
